OTTO WEEBER, OF BERLIN-CHARLOTTENBURG, GERMANY, ASSIGNOR TO SIEMENS & HALSKE, AKTIENGESELLSCHAFT, OF SIEMENSSTADT NEAR BERLIN, GERMANY, A CORPORATION OF GERMANY

STATIC AND MAGNETIC SHIELD

Application filed June 18, 1930, Serial No. 461,927, and in Germany June 19, 1929.

This invention relates generally to shielding devices and more particularly to a shield construction utilizing layers of different materials.

5 The use of copper as working material for the shielding of self-induction coils or other parts of radio circuits against the influence of external electric fields is well known. When dimensioning the thickness of the copper sheets it was found that the sheet had to be made of a greater thickness than really necessary for shielding purposes due to the demands of mechanical strength. Since copper sheeting is very expensive and since, for 10 instance in radio receiving apparatus with several tubes, considerable quantities of copper sheeting had to be employed for the shielding of the individual self-induction coils and other parts a considerable increase 15 in the cost of the receivers would result.

It is, therefore, an object of my invention to greatly cut down the cost of radio receivers and other radio apparatus in general by 20 constructing the shield of preferably two materials one known for its cheapness and strength and the other for its good shielding properties.

Other objects of the invention will be apparent in the following specification when 25 read together with the drawing, the two figures of which illustrate schematically a shield made in accordance with the invention.

According to this invention there is used, 30 say, instead of pure copper sheeting, aluminum sheeting which is coated with copper. The copper coating may for instance be applied by means of electrolysis, but more suitably by means of rolling on, since this is cheaper. It is possible in this manner to 35 combine the small thickness of, say for instance, the copper wall necessary for the shielding with sufficient mechanical stability. When using copper plated sheets covered on both sides there result further electrical advantages which show up particularly 40 in the case of lower frequencies.

In the drawing, a deeply drawn body 1 in the form of a cylinder having a closed 45 end terminates in a flange 2 which is provided with holes 3, 4 for the mounting. The

flange 2 may be integral with the body portion 1 as shown or fixed thereto.

While I have described my invention as comprising the use of aluminum and copper it is evident that any combination of elements 55 or materials may be used as for instance aluminum electroplated with zinc, sheet iron or steel and copper or in fact any usual plating material.

I claim:

1. Static shield, particularly for self-induction coils, and of special advantage in radio receiving arrangements, characterized in that it consists of copper coated aluminum sheeting. 60

2. Shield according to claim 1, characterized in that the copper coating is disposed on both sides of the sheet. 65

3. An electromagnetic shield adapted to 70 limit the field produced by an element used in radio signalling and to prevent said element from being affected by other electrical fields originating in the vicinity thereof comprising, a shield composed of a layer of non-ferrous metal which has a specific gravity 75 constant substantially less than the specific gravity constant of copper, and a layer of highly conductive metal attached to said first named layer.

4. A shield as recited in claim 3 in which 80 the metal of said first named layer is of material shape retaining strength and said second named layer is of copper.

In testimony whereof I affix my signature. 85

OTTO WEEBER.
